SHOE TREE

Donald B. Mackay, New York, N. Y.

Application April 9, 1941, Serial No. 387,580

5 Claims. (Cl. 12—128.6)

This invention relates to shoe trees and more particularly to an article of this character provided with means by which the tree may be adjusted to accurately fit shoes of different size and the adjustment thereof, when secured, may be maintained.

At the present time shoe trees are provided with various types of adjusting means, but such means generally employed permits only a rough adjustment of the tree within the shoe.

The primary object of the present invention is to provide an adjusting means by which an accurate and snug fit of the tree within the shoe is attained and when the proper adjustment has been once secured, such adjustment may be indefinitely maintained.

More particularly, the invention contemplates the provision of an adjusting means by which the forward or toe portion of the tree may be spaced at a selected distance from the rear or heel portion, said adjusting means including a rack and pinion for smooth operation, and means by which movement of the rack and pinion relative to one another is prevented once the proper adjustment is secured.

In the accompanying drawing forming a part hereof, Fig. 1 is a side elevation of a shoe tree constructed in accordance with the invention; Fig. 2 is a sectional view on the line 2—2 of Fig. 1, looking in the direction of the arrows; Fig. 3 is a plan view of the rear or heel portion of the shoe tree showing the adjusting mechanism; Fig. 4 is a horizontal sectional view through the adjusting mechanism; Fig. 5 is a view of the rear or heel portion of the tree with the adjusting mechanism removed; and Fig. 6 is a view of the underside of the pinion and attached adjusting knob.

As shown in Fig. 1 of the drawing, the shoe tree is primarily composed of two main parts, that indicated at 1 constituting the forward or toe portion of the tree and that indicated at 2 being the rear or heel portion. These parts may be made of any suitable material such as wood, metal or the like and may be generally of conventional form. The rear portion is provided on its top 3 with a suspension loop 4 pivotally mounted in the lugs 5 formed on the plate 6 which is secured by screws 7 to the top of the portion 2 of the shoe tree.

The forward part 1 of the shoe tree is provided with a flattened top surface 8 to which is secured, by the screws 9, a hinge leaf pivotally secured to a slotted hinge leaf or plate 11 by means of the pintle 12. The plate 11 has its longitudinal side

edges bent downwardly to form guide flanges 13 which are slidable in the parallel slots 14 formed in the flat top 15 of the rear or heel portion 2 of the shoe tree.

The leaf 11 is also formed with a centrally disposed, longitudinally extending, slot 16, one edge of said slot being provided with a plurality of teeth 17 constituting a rack and in mesh with a pinion 18 secured or formed on the bottom of a knurled adjusting knob 19. The adjusting knob and attached pinion 18 are rotatable on a screw 20 received in an internally threaded bushing 21 sunk in the rear portion 2 of the shoe tree, as clearly indicated in Fig. 5. Rotative movement of the bushing 21 within the portion 2 of the shoe tree is prevented by means of a pin 22 acting as a set screw against the side of the bushing. The screw 20 is provided with a winged head 23 in order to enable it to be manually tightened when desired to hold the knob 19 and pinion 18 against rotative movement, as will be explained.

From the foregoing, the operation of the improved shoe tree will be readily understood. When the tree is to be fitted into a shoe, the parts are in the position shown in Fig. 1, at which time the screw 20 is unthreaded out of bushing 21 for a sufficient extent so that the adjusting knob 19 and pinion 18 may be manually rotated. The shoe tree is placed within the shoe and then the knob 19 is rotated to cause the pinion 18 to move the leaf 11, said leaf forcing the portion 1 of the shoe tree away from portion 2 to the required extent to cause the tree to fit snug within the shoe. Because of the rack and pinion engagement between the two parts 1 and 2 of the shoe tree, the operation of the device is extremely smooth and an accurate and snug fitment of the tree within the shoe can be obtained. As soon as the tree is fitted within the shoe by adjustment

of the parts as above mentioned, the position of the parts 1 and 2 relative to one another may then be maintained by tightening the screw 20 so that the head of the same bears firmly down upon the adjusting knob 19 and holds the same against rotative movement. The knob 19 being thus clamped against leaf 11, holds leaf 11 tightly against the flat top 15 so that the several parts are thus held in clamped relationship and cannot be shifted until the screw 20 is first manually loosened.

By means of the arrangement described, adjustment of the shoe tree is smoothly and easily secured and maintained.

What I claim is:

1. A shoe tree having a toe portion and a heel

portion, the toe portion having a hinge, the hinge having a leaf slidably engaging the heel portion, said leaf being provided with an elongated slot, a toothed rack disposed within the slot, a screw extending through said slot and received into the heel portion, a manually rotative pinion through which the screw passes, said pinion being in meshed engagement with the rack and adapted to be held against rotative movement when the screw is tightened.

2. A shoe tree having a toe portion and a heel portion, the toe portion having a hinge, one leaf of said hinge being secured to the toe portion, the second leaf thereof being in slidable engagement with the heel portion, guide means in the heel portion for engaging said second leaf, said second leaf being provided with a slot, one edge of said slot being formed with a plurality of teeth, an internally threaded bushing fixed in the heel portion, a screw adjustable in said bushing, a manually rotative pinion on said screw and located within the slot and in meshed engagement with the teeth thereof, and elements on said pinion for engagement by the screw when said screw is tightened in the bushing to hold the pinion and second leaf against movement.

3. A shoe tree having a toe portion and a heel portion, each of said portions being provided with a flat upper face, a hinge attached to the flat upper face of the toe portion, said hinge having a leaf overlying the flat upper face of the heel portion, said face of the heel portion being provided with guide grooves, the leaf having edge flanges guided in said grooves, the leaf being formed with a toothed rack, a screw threaded vertically into the

5 heel portion, said screw extending through the slot in the leaf, a pinion disposed on the screw and located in the slot and in meshed engagement with the rack, a knob on said pinion, and an enlarged head on the screw for engagement with the knob when the screw is tightened to hold the knob against the leaf and prevent rotative movement of the pinion with respect to the rack.

10 4. A shoe tree provided with a toe portion and a heel portion, a hinge having a leaf fixedly attached to one of said portions and having a second leaf slidably attached to the other portion, the slidable leaf being provided with means guided by the shoe tree portion over which said leaf is slidable, said shoe tree portion having a rotatively mounted pinion, a rack carried by the slidable leaf and engaging the pinion, and clamping means by which the slidable leaf is clamped between a part of the pinion and the shoe tree portion over which said leaf is slidable, and the pinion and said slidable leaf thereby held against movement.

15 5. A shoe tree having a toe portion and a heel portion adjustably connected thereto, the connection between the toe and heel portions including a rack overlying the heel portion, a screw adjustable in the heel portion, a pinion meshed with the rack and rotatively carried on the screw and adapted by manual rotation to move the rack, said screw when tightened, acting to clamp the rack and pinion between it and the heel portion to thereby hold said rack and pinion against movement.

DONALD B. MACKAY.
